US00D859384S

(12) **United States Design Patent** (10) Patent No.: **US D859,384 S**
(45) Date of Patent: **** Sep. 10, 2019**

(54) **ELECTRONIC DEVICE**

- (71) Applicant: **Samsung Electronics Co., Ltd.**, Suwon-si (KR)
- (72) Inventors: **Sungkwon Kim**, Seoul (KR); **Kwanue Hong**, Yongin-si (KR); **Jeisung Park**, Gwacheon-si (KR); **Seo Lee**, Yongin-si (KR); **Seungchan Lee**, Seoul (KR); **Yonghee Cho**, Seoul (KR)
- (73) Assignee: **Samsung Electronics Co., Ltd.**, Suwon-si (KR)
- (**) Term: **15 Years**
- (21) Appl. No.: **29/650,184**
- (22) Filed: **Jun. 5, 2018**

Related U.S. Application Data

- (63) Continuation of application No. 29/586,187, filed on Dec. 1, 2016, now Pat. No. Des. 824,375.

(30) **Foreign Application Priority Data**

Jun. 3, 2016 (KR) 30-2016-0027196

CLAIM

We claim the ornamental design for an electronic device, as shown and described.

DESCRIPTION

FIG. 1 is a rear perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures depict portions of the electronic device that form no part of the claimed design.

1 Claim, 5 Drawing Sheets
